UNITED STATES PATENT OFFICE.

GEORGE A. HORN, OF NEWARK, NEW YORK.

FENCE.

SPECIFICATION forming part of Letters Patent No. 256,433, dated April 11, 1882.

Application filed March 1, 1882. (No model.)

To all whom it may concern:

Be it known that I, GEORGE A. HORN, of Newark, in the county of Wayne and State of New York, have invented a new and useful 5 Improvement in Fences, which improvement is fully set forth in the following specification and accompanying drawings.

My invention relates to farm-fences, and to the particular class known as "wire-bound rail-fences;" and the object of the invention is to apply the binding-wire at the angles of the fence in such a manner that the top rail of each panel may be used in each case for a lever in straining said binding-wire upon the 15 rails, thus doing away with the extra piece or lever heretofore employed.

In the accompanying drawings, Figure 1 represents a plan of a portion of a worm rail-fence, and Fig. 2 a perspective view of the 20 same.

Referring to the figures, *b* represents the rails of a worm-fence laid up in the usual manner by crossing near the ends.

g are pieces of suitable wire or cable binding the rails together at the respective angles of the fence.

The pieces of wire or cable *g* are applied in this manner: The rails *b* of the first panel, *A*, of the fence are all laid in place, and also of 30 the next panel, *B*, with the exception of the top rail, *a*, one end of which only is put in place on the upper rail of the panel *A*, the other end resting on the ground, as shown. One end of the wire *g* is then secured to the 35 upper rail of the first panel, *A*, near the angle, as shown at *e*, by winding it around said rail or otherwise, and the wire is then carried downward under the lowest rail, *f*, of the panel, thence upward and fastened to the inclining upper rail, *a*, as shown at *e*, at some distance from the point of bearing *d* between 40 said rail and the top rail of the panel *A*. Now, when the lower end of the rail *a* is raised to its place on the fence (shown in dotted lines) 45 the said rail, on account of the manner in which the wire is attached, acts as a lever to strain and tighten the wire upon the rails, binding the whole firmly together. No extra piece or lever is necessary to tighten the bind-

ing-wire at each angle, as has heretofore been 50 employed, the top rail of each panel being used as a lever for the purpose, which materially lessens the expense of construction of this class of wire-bound fences.

If the fence be made high, or if it be necessary to secure only the upper rails, the wire, as a matter of economy, need not extend to the bottom rail, but under one of the intermediate rails of the panel, as shown in dotted line at *h*.

A fence thus constructed is firm and strong, and cannot be easily blown down by the wind or have the upper rails displaced by cattle or from other causes, and it may be rapidly constructed.

Worm rail-fences having the rails of the panels held or bound together by wire at the intersection of the rails have been known before, such, for instance, being shown in patents to Lane, No. 209,902, in which a wire band or loop 70 passed around the ends of the rails is tightened upon the rails by being twisted by means of the top rail of a panel thrust through the loop and swung horizontally to place on the fence; to Gunn, No. 195,503, in which the wire 75 loop passed over the ends of the rails is drawn tight by means of a wedge forced under the top rail; and to Green, No. 239,656, in which the wire loop is tightened by being turned into a twist by means of a suitable lever carried 80 with the operator.

I do not claim broadly the principle of securing the rails of a fence by means of a wire loop or band; but

What I claim as my invention, and wish to 85 secure by Letters Patent, is—

1. The method of constructing a worm rail-fence by securing one end of a piece of wire or cable to the top rail of a panel near the point of intersection of said rail and the top 90 rail of the adjacent panel, then carrying said wire or cable down under the end of one of the lower rails of said panels, bringing it upward and attaching it to the top rail of said adjacent panel while lying in an inclined position, substantially as shown, and finally raising the free end of said inclined rail to its 95 place upon the fence, so that it will act as a

lever in straining said wire or cable, substantially as set forth.

2. A worm rail-fence of common construction, having the two ends of a piece of wire or cable secured to the respective top rails of adjacent panels near the point of intersection of said rails, said wire or cable extending under the ends of the rails of said panels, as shown,

the rails of the fence contained within the circuit of the wire being held firmly together by the same.

GEO. A. HORN.
